UNITED STATES' PATENT OFFICE.

ALLEN A. TIRRILL, OF SCHENECTADY, NEW YORK.

OPERATING CORD OR CHAIN FOR SWITCHES.

1,031,400.

Specification of Letters Patent.

Patented July 2, 1912.

Application filed April 13, 1910. Serial No. 555,266.

To all whom it may concern:

Be it known that I, ALLEN A. TIRRILL, a citizen of the United States, residing at Schenectady, in the county of Schenectady and State of New York, have invented certain new and useful Improvements in Operating Cords or Chains for Switches, of which the following is a specification, reference being had therein to the accompanying drawing.

This invention relates to improvements in operating cords or chains for switches and the like, the same in general respects having reference particularly to means for detachably connecting a suspended operating cord or chain to an actuating part of a switch, as set forth and described in my copending application executed of even date herewith.

The present improvements embrace instrumentalities for engagement with that type of operating cord or chain commonly styled a "ball chain," but it will be apparent that the device is capable of use in other connections.

A convenient embodiment of the invention comprises a ball chain, and means for connecting the same to a rotatable actuating sheave or other movable part of a switch mechanism, comprising an offset projection adapted to engage the said switch part, and a catch adapted to engage beneath one of the end balls of the chain.

An ancillary feature of the invention embraces the provision of a ball or knob for the end of the chain, and means for connecting the same to the chain or cord so that the ball will be free to rotate with reference to the latter.

The novel features of construction and arrangement will be apparent from the detailed description hereinafter when read in connection with the accompanying drawings forming part hereof and wherein a convenient embodiment of the invention is illustrated.

In the drawings, Figure 1 is a perspective view of a fragmentary portion of a switch showing my improved chain applied thereto, Fig. 2 is a perspective view of the detachable connection or catch, Fig. 3 is a transverse section showing the engagement of the catch with the chain, Fig. 4 is an elevation of the chain showing the ball or knob at the lower end thereof in section, and Fig. 5 is a bottom view of the ball or knob.

Referring more specifically to the draw-

ings wherein like reference characters designate corresponding parts in the several views, A represents an actuating sheave or rotatable part of a switch, the periphery of which is grooved to receive the chain to be hereinafter described, and a portion of the periphery being slotted as at C.

D is a ball chain of any ordinary or preferred structural formation to one end of which my improved connecting device E is secured, while at the other end my improved ball or knob construction F is fastened. The connecting device E has an offset T-head F' adapted to detachably engage the slotted portion of the periphery of the sheave, as illustrated, and a curved snap catch portion H adapted to form a seat therein for the uppermost ball of the chain and comprising oppositely disposed fingers h notched as at h' to form an opening i for the intermediate portion I between the balls of the chain, the outer ends of the fingers being arranged to spring into substantially closed relation to secure the ball to the seat therein.

From this construction it is seen that the chain may be slipped through the retaining fingers into the seat provided for the uppermost ball of the chain by simply slipping the connecting portion I between the balls of the chain through the fingers, the fingers yielding apart sufficiently for that purpose and springing shut as before noted. The pulling ball or knob F is made of hard rubber, porcelain or equivalent material, and is secured to the chain by a small washer J passing over the connecting portion I between the lowermost balls. The washer is of a shape to seat within a recess K in the ball and engage a shoulder L therein, an aperture M in the top of the ball enabling the chain to pass therethrough. In this way, the ball is freely mounted on the chain and may be readily removed or attached by simply slipping the ball upwardly on the chain and correspondingly removing or applying the spring or snap washer. When fastened in this manner, the ball is capable of rotation or play with reference to the chain at all times.

While I have herein disclosed one specific embodiment of the invention, it is to be understood that the invention is capable of embodiment in forms and devices other than that set forth herein, as will be apparent to those skilled in the art.

Claims:

1. A switch of the character described comprising a pull chain, a ball sleeved thereon, and means for preventing separation of the ball from the chain comprising a snap washer engaging between the adjoining links of the chain and abutting the ball.
2. A switch attachment of the character described comprising a pull chain, a ball 10 sleeved thereon, and means for preventing separation of the ball from the chain comprising a snap washer engaging between adjoining links of the chain and abutting the ball, said ball having a recessed portion for 15 the accommodation of the washer and a shoulder for contact therewith.
3. In an attachment of the character described, a pull chain, a ball sleeved thereon, and a detachable device engaging the chain 20 between adjoining links thereof to prevent the ball from separating therefrom.
4. In an attachment of the character described, a pull chain, a ball sleeved thereon, and a detachable device engaging the chain 25 between adjoining links thereof to prevent the ball from separating therefrom, the ball having a recessed portion for the accommodation of said device.
5. A switch attachment of the character 30 described comprising a pull chain, a ball sleeved thereon, and detachable means for preventing separation of the ball from the chain comprising a split washer engaging between adjoining links of the chain and 35 abutting the ball, said ball having a recessed portion for the accommodation of the washer and a shoulder for contact therewith.
6. An attachment of the character 40 described comprising a connecting device having an attaching portion and a snap catch adapted to engage on operating cord comprising an offset slitted portion adapted to 45 close around the cord, one of the fingers of the slitted portion being notched to constitute an intermediate opening.
7. An attachment of the character 50 described comprising a connecting device having an offset attaching portion and a catch adapted to engage an operating cord comprising an offset slitted portion, the fingers 55 of the slitted portion being notched to constitute an intermediate opening.
8. An attachment of the character 60 described comprising a connecting device having an offset attaching portion and a catch adapted to engage an operating cord comprising an offset slitted portion, curved to 65 constitute a ball seat, and the fingers of the slitted portion being notched to constitute an intermediate opening.
9. An attachment of the character de- 70
- scribed comprising a connecting device having an offset attaching portion and a catch 65 adapted to engage an operating cord comprising an offset slitted portion, the fingers of the slitted portion being notched to constitute an intermediate opening, the ends of the fingers being adapted to approach each other to close said opening.
10. An attachment of the character 75 described comprising a connecting device having an offset attaching portion and a catch adapted to engage an operating cord comprising an offset slitted portion curved to constitute a ball seat, the fingers of the slitted portion being notched to constitute an intermediate opening, the ends of the fingers being adapted to approach each other to close said opening.
11. An attachment of the character 80 described comprising a connecting device having an attaching portion and a snap catch adapted to engage an operating cord comprising an offset slitted portion adapted to close around the cord, the fingers being bent to constitute a ball seat, and one of the fingers being notched to constitute an intermediate opening.
12. A device of the class described comprising a coupling member having a bent 85 end portion slotted from its extremity inwardly, the slotted portion being contiguous to the intermediate connecting portion and forming therewith a retaining seat or socket.
13. An attachment of the character 90 described, comprising a connecting device having an attaching portion and a springy slitted portion adapted to engage an operating cord and to close transversely around the cord to prevent escape of the latter from 95 the slitted portion.
14. An attachment of the character 100 described, comprising a connecting device having an attaching portion and a springy slitted portion adapted to engage an operating cord and to close transversely around the cord to prevent escape of the latter from the slitted portion.
15. An attachment of the character 105 described, comprising a connecting device having an attaching portion and releasable means adapted to close transversely around an operating cord to confine the cord there- 110 within.

In testimony whereof I affix my signature in presence of two witnesses.

ALLEN A. TIRRELL.
